UNITED STATES PATENT OFFICE.

THOMAS F. SOMERS, OF NEW YORK, N. Y., ASSIGNOR TO BIRDSEY-SOMERS COMPANY,
OF NEW YORK, N. Y., A CORPORATION OF NEW YORK.

CORSET-STEEL.

1,077,861.

Specification of Letters Patent.

Patented Nov. 4, 1913.

Application filed April 16, 1912. Serial No. 691,205.

To all whom it may concern:

Be it known that I, THOMAS F. SOMERS, a citizen of the United States, and resident of the city, county, and State of New York, have 5 invented certain new and useful Improvements in Corset-Steels, of which the following is a specification.

This invention relates to what are ordinarily termed corset steels used for the purpose of stiffening corsets and other articles of wearing apparel, but it will be understood that the articles are not necessarily made of steel and may be made of any suitable material.

15 The present invention is an improvement on that disclosed in the patent of J. E. Doolittle No. 835,350 granted November 6, 1906.

The object of the invention is to secure the desired degree of flexibility at the end portions of the blade or stiffening member not only at its ends but at its intermediate portion and to also secure greater stiffness at a point between the ends which will not interfere with the requisite flexibility of the 25 member.

The novel features of the invention will be apparent from the following description taken in connection with the accompanying drawings.

30 In the drawings, Figure 1 is a face view of a corset steel embodying my invention; Fig. 2 is an edge view; Fig. 3 is a cross section.

As shown in these drawings, the main 35 body portion of the device is made in the shape of a long flat member 1 which may be made of steel or of any other suitable material which has the necessary strength and flexibility. A strengthening strip 2 is placed 40 longitudinally of the member 1 at the points where it is desired to strengthen the member and as shown it is along the central portion. It is preferably in the shape of a flat strip of the same width as the member 1 and 45 fits closely against it but is not rigidly secured to it at any point. Its ends are preferably rounded so as to present no sharp

points to catch in the wearing apparel. A wire 3 is wrapped around the member 1 overlapping the strip 2 from one end to the other 50 so as to securely hold the strip in place and to serve the additional function of strengthening the body portion 1 at the point covered by it. This wire 3 is preferably in the shape of a flat band wound closely around the 55 parts so that it will not unduly thicken or project from the body portion of the steel.

It will be observed that the strengthening strip 2 is held firmly in place but not being rigidly secured to the body portion 1, it does 60 not form a rigid brace and it allows free movement and bending of the parts limited only by the strength of the strip and the binding action of the coiled wire around it. The strengthening strip 2, not being rigidly 65 attached to the main body member 1 of the stay, is free to move a limited distance longitudinally thereof and the ends of the flat wire 3 which are wound around the member 1 beyond the ends of the strengthening strip 70 2 will form stops which are engaged by the ends of the strip 2 to limit the movement of the latter.

Having described my invention what I claim and desire to secure by Letters-Patent is,

1. A spring steel for corsets comprising a flat member having a flat strengthening strip thereon throughout part of its length, and a wire coiled around said member and strip 80 and holding said strengthening strip in place.

2. A spring steel for corsets comprising a main body portion, a longitudinal strengthening strip resting closely against said body 85 between its ends but not rigidly secured thereto, and a wire coiled closely around said strip and body.

3. A spring steel for corsets comprising a flat member, a flat strengthening strip fitting against but not rigidly secured to said member at a point between its ends, said strip being free to move bodily a slight distance lengthwise of said flat member, and a flat

wire coiled closely around said strip and member to hold said strip in place and strengthen said member.

4. A corset steel comprising the combination of a main flat body member, a flat reinforcing strip fitting against the body member and free to move a limited distance longitudinally of the same, and a flat wire coiled around the strip and member to se-

cure the parts together, said wire having its ends wound around the body member in order to limit the movement of said strip.

In testimony whereof I affix my signature in presence of two witnesses.

THOMAS F. SOMERS.
